UNITED STATES PATENT OFFICE.

FREDRIK SELMER, OF CHRISTIANIA, NORWAY.

SAND-HEATING APPARATUS FOR BUILDING PURPOSES.

Application filed October 30, 1924, Serial No. 746,901, and in Norway November 9, 1923.

My invention relates to a sand heating apparatus for building purposes.

When concrete casting and masonry has to be done in low temperatures after the 5 frost has set in, it is necessary to have the materials (sand and water) heated before use.

It is usual to heat the sand and water separately, the sand being heated by means of 10 sand heating ovens and the water in separate receptacles (pots) on a fireplace. The sand heating ovens hitherto known are liable to be overheated, and under such conditions they are apt to be pressed together by the 15 weight of the overlying sand and destroyed.

The object of my invention is to provide a combined sand heating and water heating apparatus, arranged in such a manner that the outer shell of the apparatus is supported 20 by a system of water tubes through which is passed the water to be heated. In this manner the tubes, in which the water is heated serve simultaneously as a skeleton and interior protection for the body or outer shell 25 of the sand heating apparatus.

This apparatus may be of any suitable cross section, cylindrical, triangular or the like, and may be arranged at will horizontally, vertically, or at an angle, and the 30 water-tubes arranged therein may be arranged in form of a spiral, zigzag-shaped, in form of a grate or the like.

In the following the invention shall be explained with reference to the accompanying 35 drawings illustrating several executional forms of the apparatus.

Figs. 1 and 2 are, respectively, a longitudinal section and a cross section on line 2—2, Fig. 1, of a cylindrical sand and water heating apparatus.

Fig. 3 is a cross section of a substantially triangular apparatus.

Fig. 4 is a corresponding cross section of a roof-shaped apparatus.

Fig. 5 is a longitudinal section of a further modification, Fig. 6 is a front view of the front wall of this apparatus and Fig. 7 is a cross sectional view on line 7—7, Fig. 6, illustrating also the circulation tank combined with the tubing of the apparatus.

In the executional form illustrated in Figs. 1 and 2, 1 is the outer, cylindrical shell of the sand heating apparatus, 2 is the fireplace, provided with a grate 3, from which the combustion gases pass to the stack 4.

According to my invention the water to be

used for the casting or slaking is introduced at 5 in a spiral-shaped water tube 6 arranged within the shell 1 in such manner that it is in contact with its inner wall 60 throughout and serves as a reinforcing skeleton for the same.

As will be seen from Fig. 1 the spirals may preferably be arranged closer together 65 in the part of the apparatus that is subjected to the strongest heat, this part of the apparatus being most in need of cooling.

Fig. 3 illustrates a cross section of an apparatus having a roof-shaped shell 1, open at the base, the water tube 6 being here arranged in a triangular helix forming a roof-shaped skeleton supporting the shell 1.

The modification illustrated in the cross sectional view Fig. 4 only differs from the form illustrated in Figs. 1 and 2 therein that 70 the shell 1 and its supporting tubes are arranged with a substantially triangular cross section.

In the executional forms diagrammatically illustrated in the preceding figures the 80 emptying of the water tubes in order to avoid freezing of the tubes when the apparatus is out of action at night, presents certain difficulties, it being necessary to have the water blown out by steam or air pressure. In the executional form illustrated in 85 Figs. 5 to 7 these difficulties are avoided, the arrangement being such as to enable the letting off of the water in the water tubing simply by opening a cock or tap.

The tubing in this apparatus is composed of a longitudinal main tube 7 placed along the ridge of the roof-shaped shell 6, the latter having a cross section resembling a gothic arch, similar longitudinal tubes 8 are 95 placed along the lower edges of the shell 6; the tubes 7 and 8 are interconnected by aid of a number of rib-shaped tubes 9, the form of said tubes conforming with the cross sectional curve of the shell 6.

The two tubes 8 may also be interconnected through horizontal tubes 10, a number of which may be placed so close to each other as to form a waterfilled grate.

The two tubes 8 protrude beyond the front 105 wall 11 (Fig. 6) of the apparatus, being provided with cocks or couplings 12, one of which may eventually be arranged to connect the water tube system with a conduit of water under pressure (not shown).

In Fig. 7 is illustrated a circulation tank 13, connected to the tube 7 by a tube 14, and

to the tubes 8 by a tube 15, thereby ensuring a circulation of the water heated in the tubes 7, 8 and 9. The heated water to be used for slaking or casting is tapped from the cock 16 of tank. This cock 16 is placed at such a level relatively to the port 17, through which connection is had with the tube system of the heating apparatus, that the level in the tank will always cover the port 17, thus ensuring a constant circulation of the water through the tube system of the water heater.

As will be seen the entire tube system of the sand heater may be emptied by opening one or both of the cocks 12. When both of

these cocks are closed the water will circulate continuously through the tank and the water tube system.

Claim:

A combined sand and water heating apparatus comprising a shell, a fireplace, a water tubing including arch forming portions arranged in direct supporting and heat interchanging relation with said shell, about said fireplace, and means for circulating water through said tubing.

In testimony that I claim the foregoing as my invention, I have signed my name.

FREDRIK SELMER.
